UNITED STATES PATENT OFFICE.

BROOKS BUTLER, OF MAPLEVALLEY, WISCONSIN.

CONTAINER-HOLDER.

1,400,798.

Specification of Letters Patent. Patented Dec. 20, 1921.

Application filed May 20, 1921. Serial No. 471,062.

To all whom it may concern:

Be it known that I, BROOKS BUTLER, a citizen of the United States, residing at Maplevalley, in the county of Oconto and State of Wisconsin, have invented certain new and useful Improvements in Container-Holders, of which the following is a specification, reference being had to the accompanying drawings.

10 This invention relates to container holders, and more particularly to a holder for supporting milk pails and the like.

15 It is an object of the invention to provide a holder of this character capable of supporting a container in spaced relation to the ground, and for gripping the container to prevent accidental disengagement thereof from the holder.

20 It is another object of the invention to provide a holder of this character which is adjustable to accommodate various sizes of pails.

25 It is a further object of the invention to provide a holder of this character embodying a plurality of pail supporting members, certain of said members being provided with jaws for engagement with the pail, while the remaining supporting member is provided with means for engagement of the pail with the jaws for adjustment of the supporting members.

30 A still further object of the invention is to provide a holder of this character including a plurality of supporting members adjustable with respect to the adjacent member, and arranged to be detachably connected to each other.

35 With these and other objects in view the invention consists in the improved construction and arrangement of parts to be hereininafter more particularly described, fully claimed and illustrated in the accompanying drawings in which:

40 Figure 1 is a view in elevation of a container holder constructed in accordance with an embodiment of the invention,

Fig. 2 is a top plan view,

Fig. 3 is a side elevation of the primary supporting member, and

45 Fig. 4 is a side elevation of one of the secondary supporting members.

Referring to the drawings, 5 designates a holder embodying a supporting member 6, having a supporting leg 7 formed on and

projecting in angular relation to the end 8 of said member, one end portion of said leg projecting beyond the upper face of the supporting member. The opposite end portion 9 of said member is enlarged and offset and provided with a plurality of transversely extending ridges 10 which coöperate with each other to form recesses 11, said recesses extending laterally of the end portion 9. An eye 12 is formed on the extremity of the enlarged end portion to permit the device to be supported when not in use, and also to serve as a finger piece in order to properly position the holder.

55 The remainder of the holder comprises supporting members 13 and 14, the supporting member 13 being offset at its intermediate portion 15 so as to dispose one end portion of said member below the opposite end portion, the last mentioned end portion including a supporting leg 16 which is reinforced by a brace member 17. The end portion 18 of the supporting member 13 is provided with a slot which extends from the intermediate portion to the extremity of said end, the purpose of which will be hereininafter described. The opposite end portion of the supporting member 13 includes an extension 19, which is extended back upon the member 13 to form a container engaging jaw.

60 The structure of the supporting member 14 is similar to the structure of the supporting member 13, the slotted end portion of the member 14 being adapted to extend over the slotted end portion of the members 13 so that the slots in said members register. The overlapping portions of the members 13 and 14 are adapted to be disposed in one of the recesses 11 of the supporting member 6, each of said recesses having an opening formed therein for the reception of a bolt or like fastening means 20, said fastening means being arranged to extend through the registered slots of the members 13 and 14. By this means, the members 13 and 14 may not only be adjusted toward and away from each other according to the size of the pail, but the length of the supporting member 6 may also be increased or decreased by disposing the overlapping end portions of the supporting members 13 and 14 in the desired recess of the supporting member 6. This novel structure eliminates the necessity of a fourth

supporting member, and at the same time, provides a wide range of adjustment, so that regardless of the size of the container, it may be properly positioned upon the holder.

5 In order to prevent accidental disengagement of the container from the holder, there is provided novel means in the form of jaws formed on the supporting members 13 and 14, said jaws being adapted to engage the 10 lower portion of a pail or like container. The leg 7 of the supporting member 6 is provided with a leaf spring 21 which is secured to the upper end portion of the leg 7, one end of said spring extending beyond the 15 extended upper end portion of the leg. A clamp 22 including a finger piece 23, is secured to the upper end portion of the spring 21, the lower face of the clamp 22 being adapted to extend over the extended end portion 20 of the leg 7. It will be noted that the inner face 24 of the clamp member is substantially rounded so as to permit unobstructed movement of the clamp toward the container. In applying the container it is 25 only necessary to engage the lower portion of one side of the container with the jaws of the members 13 and 14 and then force the pail downwardly against the rounded face of the clamp 22, thereby causing the 30 pail to be urged toward the supporting members 13 and 14 so that accidental disengagement is impossible. The supporting members 13 and 14 are curved longitudinally and when connected to the supporting member 6 35 extend toward the leg of said supporting member. The offset portions of said supporting member permit the means of connection of the supporting members to each other to be disposed below the surface of the 40 supporting members with which the container is engaged so that there is no danger of the container being positioned unevenly on the holder.

From the foregoing it will be readily 45 seen that this invention provides a novel form of container holder having a variety of adjustments which readily renders the device capable for use in connection with all kinds of pails or like containers and 50 wherein the weight of the pail is substantially supported by a three legged holder. The center of gravity is disposed to one side of the connection of the supporting members to each other, in view of the fact that 55 the center of the pail is positioned substantially over the intermediate portion of the supporting member 6. The holder is particularly adapted for use in milking, as it holds the milk pail the desired distance from 60 the ground, so that splashing of the milk is impossible. At the same time, accidental tilting of the pail is also eliminated. It is of course to be understood that I do not desire to limit myself to this precise arrangement and use of the holder, as minor 65

changes may be made in the structure to permit use of the device for various purposes.

What is claimed is:

1. A container holder of the character described comprising supporting members, each of said members having a leg extending from one end, the opposite end of one of said members being enlarged and provided with a plurality of laterally extending channels, the opposite end portions of the remaining members being slotted and adapted to overlap each other substantially in parallel relation, said overlapping portions being disposed in one of said channels, and means for connecting said members to each other. 75

2. A container holder of the character described comprising a primary supporting member including a leg, a spring press 85 clamp carried by the upper portion of the leg, the opposite portion of said supporting member being enlarged and having a plurality of spaced ridges extending laterally of said end to provide channels, secondary 90 supporting members, each of said members having a leg projecting from one end thereof, and having its opposite end slotted, the slotted portion of each of the secondary holding members being adapted to register, 95 said primary holding member being adapted to receive said slotted end portions of the secondary supporting members, means extending through one of the channels and the slotted portion of the secondary supporting 100 members for connecting said secondary supporting members to the primary supporting member, and means carried by the first mentioned end of each of the secondary supporting members and cooperating with the 105 clamp of the primary supporting member to hold a container.

3. A pail holder of the character described comprising a primary supporting member having a leg projecting from one 110 end thereof, an extension carried by the upper portion of the leg, a spring secured to the leg, a clamp member carried by the upper end of the spring and projecting over the extension of the leg, the opposite end 115 portion of the supporting member being enlarged, said enlarged portion having channels, a pair of secondary supporting members, each of said members including a leg, a jaw projecting from 120 the upper end of the leg and toward the supporting member, the opposite end of said secondary supporting member being offset and longitudinally slotted, one of said channels being adapted to receive the slotted 125 portions of the secondary supporting members, means for securing the slotted end portions of the secondary supporting members to the primary supporting member, said clamp of the primary supporting mem- 130

- ber cooperating with the jaws of the secondary supporting members to prevent accidental disengagement of a pail from the holder.
- 5 4. A container holder of the character described comprising a main supporting member arranged to extend substantially laterally of an object to be supported, a pair of auxiliary supporting members arranged to
- 10 overlap each other substantially in parallel relation and transversely of one end of the main supporting member and to one side of the center of the object, and fastening means for connecting said auxiliary supporting
- 15 members to the end portion of the main supporting member.
5. A container holder of the character described comprising a main supporting member having a supporting leg on one end, the opposite end of said member having 20 channels, a pair of auxiliary supporting members having legs on one end thereof, the opposite ends of said auxiliary supporting members being arranged to overlap each other within one of the channels of the 25 main supporting member, and fastening means for connecting said supporting members to each other within the channels.

In testimony whereof I hereunto affix my signature.

BROOKS BUTLER.
